UNITED STATES PATENT OFFICE.

JAMES DIXON CHURCHILL, OF UPPER HOLLOWAY, COUNTY OF MIDDLESEX,
ENGLAND.

SAFETY-VALVE APPARATUS FOR STEAM-BOILERS.

SPECIFICATION forming part of Letters Patent No. 256,853, dated April 25, 1882.

Application filed February 14, 1881. (Model.) Patented in England July 1, 1880.

To all whom it may concern:

Be it known that I, JAMES DIXON CHURCHILL, a subject of the Queen of Great Britain and Ireland, residing at Upper Holloway, in the county of Middlesex, Kingdom of Great Britain and Ireland, have invented new and useful Improvements in Safety-Valve Apparatus for Steam-Boilers, (for which I have obtained a patent in Great Britain, No. 2,693, bearing date July 1, 1880,) of which the following is a specification.

My invention consists in controlling the safety-valve of a steam-boiler by steam-pressure acting on a piston connected to the safety-valve and working in a cylinder, the distribution of steam to which is effected in such manner that so long as the pressure in the boiler does not exceed the maximum for which the apparatus is set the steam-pressure against the piston will be on that side tending to keep the safety-valve shut; but on the said maximum pressure in the boiler being exceeded steam will be allowed to escape from that side of the piston against which it has been acting, thus relieving the safety-valve of its load and allowing it to open; and should it stick or not open sufficiently steam will be admitted to so act on the piston as to cause opening of the safety-valve, (subsequent arrestation of the piston being effected by the closing of the steam-supply and exhaust ports,) the amount of movement of the piston being regulated by the varying pressure of steam in the boiler, and a fall in that pressure below the maximum for which the apparatus is set readmitting steam to act on such side of the piston as to reclose the safety-valve.

Referring to the accompanying sheets of drawings, Figure 1 is an elevation, partly in section, of so much of a safety-valve apparatus as is necessary to an understanding of my invention. Fig. 2 is a plan. Fig. 3 is a section in line 1 2 of Fig. 1.

a is a cylinder in communication by *b* with the boiler. This cylinder is truly bored from *c* to *d*—a distance corresponding to the depth of its contained piston *e*, which is provided with packing-rings at *f*. This piston is loaded by a spring, *g*, interposed between the piston and a cross-head, *h*, adjustable by turning the

nuts *i* on the bolts or rods *j*. The piston-rod *k* passes freely through the cross-head *h*, and has jointed to it at *l* a lever, *m*, the joint being so made as to allow of the slight radial movement of the lever.

n *p* is a pin serving as fulcrum to the levers *m o*. This pin is fixed in an arm or lever, *o*, the part *n* being eccentric to the fulcrum *p* of this lever. (See Fig. 3.) The pivot constituting the fulcrum *p* of the lever *m* is supported in a bearing-piece, *q*, fixed on the right-hand rod *j*. The arm *m'* of the lever *m* is connected by rod *r* to a D-slide in the steam-chest *s* of the cylinder *t*.

The ports are arranged as follows: The top one communicates with the bottom of the interior of the cylinder, the next lower port communicates with the exhaust, and the third or lowest communicates with the top of the interior of the cylinder.

In Fig. 1 I have supposed the piston in cylinder *t* to be at the bottom of the cylinder, (which is the normal position,) with the full boiler-pressure above it, the port communicating with the top of the cylinder being open to the steam-supply, while the port communicating with the bottom of the cylinder is open to the exhaust. In this position the safety-valve (which is not shown, but of which *u* is the lever, and which is jointed at *v* to the piston-rod *w*) is supposed to be closed, and the piston *e* in the cylinder *a* is in its lowest position. Assuming, now, that the pressure in the boiler rises above the maximum for which the apparatus has been set by the nuts *i*, the piston *e* will be raised in the cylinder *a* against the resistance of the spring *g*, thereby tilting the lever *m* on its fulcrum *n* and moving the slide in the steam-chest *s* of the cylinder *t*.

This movement of the slide will, to begin with, close communication between the port leading to the bottom of the cylinder and the exhaust, and also will shut off steam from the port leading to the top of the cylinder. Then it will begin to open to the exhaust the port leading to the top of the cylinder, thereby reducing the pressure on the top of the piston in the cylinder *t*, whereby the safety-valve lever is held down, thus permitting the safety-valve to rise by the pressure of the steam

against that valve, while should the safety-valve not open, or should the opening thus obtained not suffice to relieve the boiler of the excess of pressure, the continued downward movement of the D-valve will admit steam to the bottom of the cylinder *t* below the piston therein, thereby bringing it into operation for assisting the opening of the safety-valve. As the piston in cylinder *t* rises it, by means of the rod *w* and the arm or lever *o*, raises the fulcrum *n* and lever *m*, thereby returning the slide in valve-chest *s* sufficiently to close the top and bottom ports to both steam and exhaust, thus retaining the piston in the position it has assumed in cylinder *t*. When the steam-pressure in the boiler is sufficiently lowered the piston *e* in cylinder *a* returns to its normal position, (see Fig. 1,) and in so doing operates the slide in the valve-chest *s*, so as to partially open the top port to the exhaust and the bottom port to the steam, thus admitting steam above the piston in cylinder *t* and returning that piston to the bottom of the cylinder, thereby closing the safety-valve. As the piston descends in its cylinder *t* and closes the safety-valve the slide in the steam-chest *s* is returned to its normal position by the movement of the arm or lever *o*, carrying the fulcrum-pin *n*.

It will be evident that in practice the details of arrangement may be varied without departing from the essential peculiarities of my invention. Thus the rod *k*, instead of being attached to a piston, *e*, working in the cylinder *a*, may be connected to one of two flexible disks, constructed of metal—such, for example, as German silver—which will not oxidize, the disk to which said rod is connected being loaded by a spring—such as *g*—and the load being adjustable by means of the cross-head and nuts, such as *k* and *i*. In such a modification the two disks may be secured together by three rings, which nip the edges of the disks, so as to form a steam-tight chamber. It is to be understood that in this case steam from the boiler will enter between the disks, and when the pressure exceeds that for which the apparatus has been set the rod *k* will be raised in opposition to the spring *g*, and the apparatus will operate in a similar manner to that already described with reference to the drawings.

In place of a pair of disks, as just described, a single disk may be employed, this disk be-

ing mounted so as to form the flexible side of a chamber within which the steam-pressure acts; or two or more pairs of disks, forming chambers the interiors of which communicate, may be used.

What I claim is—

1. In safety-valve apparatus for steam-boilers wherein the safety-valve is connected to and controlled by a piston working in a cylinder, admission and emission of actuating-fluid to and from which are regulated by a slide or valve, the combination, with such slide or valve, of a piston or its equivalent in direct communication with the interior of the boiler, said piston or its equivalent being loaded by an adjustable spring adjusted by the nuts *i*, or their equivalents, and connected to said slide or valve, substantially as herein specified. 60
2. In safety-valve apparatus for steam-boilers wherein the safety-valve is connected to and controlled by a piston working in a cylinder, admission and emission of actuating-fluid to and from which are regulated by a slide or valve operated through a lever, *m* *m'*, by a piston or its equivalent actuated by the pressure in the boiler, the combination, with said lever *m* *m'*, of an arm or lever, *o*, and a pin or projection, *n*, fixed to said arm or lever *o* in a position eccentric to its own fulcrum, said pin or projection *n* serving as the fulcrum of the lever *m* *m'*, substantially as hereinbefore described, and for the purposes specified. 75
3. In a safety-valve apparatus for steam-boilers, the combination of a cylinder, *t*, containing a piston whose rod *w* is connected to the lever *u* of the safety-valve, a slide or valve working in steam-chest *s*, a rod, *r*, a lever, *m* *m'*, to which said rod *r* is connected, an arm or lever, *o*, connected to piston-rod *w*, an eccentric fulcrum pin or projection, *n*, on which said lever *m* *m'* is mounted, a rod, *k*, connected to said lever *m* *m'*, and a piston, *e*, working in a cylinder, *a*, and loaded by a spring, *g*, adjustable by a cross-head, *h*, nuts *i*, and rods *j*, all substantially as and for the purposes hereinbefore described. 90
